(57) **CLAIM**

The ornamental design for a barbecue tool with inset grip, as shown and described.

DESCRIPTION

FIG. 1 is a front elevational view of a barbecue tool with inset grip showing my new design, the rear elevational view being a mirror image thereof;

FIG. 2 is a left side elevational view thereof;

FIG. 3 is a right side elevational view thereof;

FIG. 4 is a bottom view thereof;

FIG. 5 is a top view thereof;

FIG. 6 is a front elevational view of a second embodiment, the rear elevational view being a mirror image thereof;

FIG. 7 is a side elevational view of the second embodiment, the opposite side elevational view being a mirror image thereof;

FIG. 8 is a bottom view of the second embodiment;

FIG. 9 is a top view of the second embodiment; and,

FIG. 10 is a bottom view of a third embodiment, the front and rear being the same as the view shown in FIG. 6, the side and opposite side view being the same as the view shown in FIG. 2, and the top view being the same as the view shown in FIG. 9.

The rear elevational views are minor images of the front elevational views illustrated in FIG. 1 and FIG. 6, the side of the second embodiment not illustrated is identical to the side illustrated in FIG. 7; the third alternate embodiment includes front and rear elevations identical to FIG. 6 and side elevations identical to the side elevation illustrated in FIG. 2 and a top view identical to the top view of FIG. 9; and the broken line showings form no part of the claimed design.

The broken lines are for illustrative purposes only and form no part of the claimed design.
